UNITED STATES PATENT OFFICE.

LAWRENCE B. WEBSTER, OF MARION, INDIANA.

ROAD-ROLLER.

1,120,427.

Specification of Letters Patent.

Patented Dec. 8, 1914.

Application filed February 18, 1910. Serial No. 544,644.

To all whom it may concern:

Be it known that I, LAWRENCE B. WEBSTER, a citizen of the United States, residing at Marion, in the county of Grant and 5 State of Indiana, have invented certain new and useful Improvements in Road-Rollers, of which the following is a specification, reference being had therein to the accompanying drawing.

10 My invention relates to power driven road-rollers, and consists in the arrangements and organizations of parts hereinafter fully described and then pointed out in the appended claims.

15 In the accompanying drawings which illustrate a practical embodiment of the various features of my invention, Figure 1 is a side elevation of the complete machine; Fig. 2 is a top plan view of the machine 10 of Fig. 1 with the canopy removed and control levers omitted; Fig. 3 is a detail view 20 of parts of the machine, partly in top plan and partly in horizontal section, showing the clutch, reversing gear, and control mechanism; Fig. 4 is a detail view partly in section and partly in side elevation, showing the parts of Fig. 3; Fig. 5 is a detail view, partly in section and partly in elevation, showing some of the parts shown in 25 Fig. 3; Fig. 6 is a longitudinal section on an enlarged scale through the shaft of the friction clutch, and Fig. 7 is a longitudinal section on an enlarged scale through the rear axle and the reversing gear.

30 Referring to the drawings, the supporting frame-work of the machine comprises as its principal elements a pair of vertical, side-plates 1 extending substantially the full length of the machine and of sufficient depth to afford a strong and rigid frame as is customary in this class of machines. These side plates have suitable bearings 2 for the rear axle 3 carrying the broad rear traction wheels, and at their forward ends they are arched upward and are suitably bolted to the shank of a head post 4, which is pivotally mounted on a spindle 5 connected through a hinge joint with a fork 6, in which is journaled the broad divided front wheel or roller of the machine, all arranged in a manner now well understood. The side plates are rigidly connected and spaced by connecting plates 7, engine brackets 8, and the supports of the bearings for the power-transmitting shafts. The motor

9 of any suitable type, preferably a gasoline or other explosive engine, is carried on the frame by the brackets 8 and is provided with the usual cranked engine-shaft 10 extending longitudinally of the machine 60 and carrying the balance wheels 11 and 12 at its outer ends and entirely inside the planes of the side-plates of the frame. On the end of the engine shaft projecting toward the forward end of the machine 65 is fastened by bolts 13 the shaft 14, which is supported at its end away from the engine by the bearing 15. A hollow shaft or sleeve 16 incloses this projecting shaft, and at the end next to the engine carries a 70 friction clutch member 17 having a beveled face 18 and which is mounted to revolve therewith and slide thereon. The sleeve also carries pivoted dogs 19 and a sliding beveled collar 20 acting on the dogs and 75 adapted to cause them to press against and move the member 17 along the sleeve to push it into engagement with the balance wheel 11, which acts as a friction bell. On the hollow shaft are fastened two spur pinions 21 and 22 of unequal diameters. A transmission shaft 23 is mounted in bearings 24 below and parallel with shaft 14 and extends longitudinally of the machine, and two spur gears 25 and 26 splined on the 80 shaft 23 are connected together with a spacing sleeve 27 so that either gear can be thrown into engagement with its corresponding pinion on the hollow shaft. The sleeve 27 is shifted by a lever mechanism 85 consisting of a pivoted forked lever (not shown) connected by means of the link 30 to a change-speed hand lever 31 in easy reach of the person operating the machine. It will be observed that by reason of the 90 pinion 21 being smaller than the pinion 22, and the gear 25 which meshes with the pinion 21 being larger than the gear 26 a slower speed will be transmitted to the shaft 23 when 21 and 25 are engaged than when 22 100 and 26 are engaged.

The shaft 23 connects the sliding gears 25 and 26 with a bevel pinion 32 mounted on the opposite end of the shaft, and a pair of bevel gears 33 and 34 mesh with the bevel 105 pinion 32 on the opposite sides thereof and are free to turn about a counter-shaft 35 mounted in bearings 36 in the side plates. Upon the inner opposite faces of the bevel gears jaws are cut, and splined to the shaft 110

35 between the bevel gears is a sliding clutch 37, which by a system of levers to be fully described later, can be thrown into engagement with the jaws of either bevel gear or 5 into an intermediate non-engaging position between them. It will be observed that by reason of the bevel gears 33 and 34 meshing with the bevel pinion 32 on its opposite sides, the shaft 35 may be revolved in either 10 direction by shifting the sliding jaw clutch 37 into engagement with the associated bevel gear, or the shaft may be stationary and not revolved when the sliding clutch is disengaged from both bevel gears. The counter-shaft 35 has fastened to it a brake drum 38 around which passes the usual brake-band (not shown) which can be tightened by any suitable means, such as the usual foot lever (not shown), so that the operator can 15 control the motion of the counter-shaft. The counter-shaft 35 is provided preferably inside the side-plates 1, with the driving pinion 39 which engages with the central gear-ring 40 of the usual differential gear upon 20 the rear axle 3.

From the foregoing description it will be seen that by shifting the sliding clutch 37 into engagement with one or the other of the bevel gears a forward or backward 25 movement of the machine can be obtained and that by reason of the difference in the relative proportions of the two pairs of transmitting gears 21—25 and 22—26 the machine can be driven at a faster or slower 30 speed, at the pleasure of the operator; the machine can run either forward or backward at a slow or high speed, having exactly the same speed or travel, whether fast or slow, in both forward and backward directions.

In connection with the power-transmission mechanism above described, I have provided a system of control levers whereby the operator by a single hand-lever may throw 45 the engine out of engagement with the power-transmission system whenever the roller is stopped or reversed, thus preventing any shocks resulting from such operations from injuring the mechanism of the 50 engine.

Referring more particularly to Figs. 3, 4 and 5, I provide the jaw-clutch 37, splined on the shaft 35 with sufficient lateral movement to engage with either bevel gear or 55 lie free between them, with a loosely fitting collar 41 held in position in a circumferential groove in the jaw and engaged and moved by a forked lever 42 pivoted on the fixed bearing 43, and adapted to push the 60 jaw-clutch into engagement with either bevel gear. An angle-lever 44 pivoted at 45 to a member of the machine frame, the upright arm 46 of which lies alongside the usual segment-rack 47 and is provided with 65 the usual pawl for holding it in idle or

operative positions, is connected to the forked lever 42 by means of two connecting rods 48 and 49 and the intermediate bell-crank lever 50 pivoted at 51 on a bracket of the frame. The rod 49 is mounted on the 70 frame for reciprocating endwise movement by the bell-crank lever whose upper end engages an offset 52 thereof, and the free end of the lever 42 is yoked or forked to provide a pair of ears 53 through which the 75 rod 49 freely passes. Between the ears of the fork of the lever 42 a collar 54 is fastened on the rod 49, and a compression spring 55 is mounted on the rod 49 on each side of the collar and between it and adjacent ear of the fork of the lever 42. The engine clutch 17 and bell 11 are thrown into engagement when the sleeve 20 slidingly mounted on the shaft 16 is moved to raise the ends of the dogs 19, and causes these 85 dogs to press with their opposite ends against the face of the clutch 17 to press it into frictional engagement with the bell, and for this purpose the angle-lever 44 is connected to the loose sleeve 20 by the links 90 56 and 57 suitably supported on the frame and engaging the free end of a lever 58 fixed on a pivoted rock-shaft 59 mounted in bearings 60 and carrying a forked lever 61 engaging a collar 62 lying loosely in a circumferential groove of the part 20.

The upper end of the arm 46 is adjacent the operator's position and when the operator gives the angle-lever 44 sufficient movement to cause its pawl to drop into the left hand end notch in Fig. 4, one of the compression springs 55 will be compressed and cause the balanced forked lever 42 to turn on its pivot, thereby engaging the sliding clutch 37 with the bevel gear 34, and the same motion of the angle-lever 44 will cause the link 56 to move toward the operator and shift the lever 61 on its pivot and moves the loose sleeve 20 to raise the dogs 19 to force the clutch 17 into engagement with the bell 11. When the operator moves the angle-lever in the opposite direction so that its pawl drops into the opposite end notch, the opposite one of the compression springs is compressed and the sliding clutch 115 37 is engaged with the bevel gear 33, and as the bevel gears are on opposite sides of the bevel pinion, motion in either direction can thus be transmitted to the traction wheels of the roller by engaging either one of the bevel gears, and as the links 56 and 57 and the pivot 45 of the angle-lever 44 are all on the same straight line, when the angle-lever is moved into the position last described, it transmits to the connecting link 56 the same motion toward the operator that it had before to engage the engine clutch. It will be observed that the engine clutch is forced into engagement with the bell whenever the jaw-clutch 37 is thrown 120 125 130

into engagement with either of the bevel gears, and conversely it will be observed that whenever the jaw-clutch 37 is thrown out of engagement with either of the bevel gears, the clutch 17 is thrown out of engagement with its bell. By this means the same lever controls the engine clutch and the means for controlling the direction of travel of the machine, the arrangement being such that the engine clutch is necessarily disconnected before a reversal of travel of the machine is effected.

The fork 6 is shifted to steer the machine by chains 63 wound on drums 64 on a shaft 15 65 provided with a worm wheel 66 operated by a worm 67 on the usual steering-post 68. The steering gear is located inside the side-plate.

The engine is mounted between the side-plates and may be hung more or less low down to lower the center of gravity; the change-speed gearing and clutch are forward of the engine so that the latter is located back in the frame near the rear wheels. All the parts of the engine, and the change-speed gearing and steering gearing and differential gear are inside the side-plates so that no parts are exposed; the plates 7 forms a shield at the front end to protect the parts from dust and dirt and with the bottom extensions provides an enclosing casing for the entire mechanism.

I claim:

1. In a power propelled road roller, the combination with a frame comprising a pair of side plates, a steering wheel at the forward end thereof, an axle and pair of traction wheels mounted on said frame, and supporting the rear end thereof, a gas engine disposed between said side plates, an engine shaft extending longitudinally of the frame and having a balance wheel inside of said side plates, a transmission shaft extending longitudinally of the side plates, a change speed gear between said engine shaft and said transmission shaft, a clutch between said change speed gear and the engine shaft, a reversing gear between the transmission shaft and the axle, a lever on the frame, and connections between the lever and the clutch and reversing gear for coördinately operating the same, said speed change gear, engine shaft, transmission shaft and reversing gear being located between the side plates and between the upper and lower edges thereof whereby said parts are protected.

2. In a power propelled road roller, the combination with a frame, a steering wheel in the forward end thereof, an axle and pair of traction wheels mounted on said frame, and supporting the rear end thereof, a gas engine and engine shaft mounted on said frame, a transmission shaft, the speed changing mechanism for connecting the en-

gine shaft to the transmission shaft, a friction clutch between said speed changing mechanism and said engine shaft, a reversing gear independent of the speed changing mechanism for connecting the transmission shaft to the axle, a lever, connections between the lever and the friction clutch and connections between the lever and the reversing gear whereby the reversing gear and clutch may be coördinately operated without varying the speed transmitting mechanism.

3. In a power-propelled road-roller, the combination with a frame, a steering-wheel swiveled in the forward end, a pair of traction wheels supporting the rear end thereof of a gas engine and engine-shaft mounted on said frame, a clutch mounted on a hollow shaft which is free to turn on said engine-shaft, a speed changing mechanism mounted on said frame and connecting said clutch to a bevel pinion, an operating lever for said speed-changing mechanism, two bevel gears loose on a counter-shaft on opposite sides of the bevel pinion, a balanced clutch-sleeve splined on said counter-shaft between the two bevel gears, a lever, connections between the lever and clutch and between the lever and sleeve, said connection being so disposed that the clutch is closed subsequent to the movement of the sleeve for engagement with the beveled gears, substantially as described.

4. In a power-propelled road-roller, the combination with a frame, a steering wheel swiveled in the forward end, a pair of traction wheels supporting the rear end thereof, of a gas engine and engine shaft mounted on said frame, and engine clutch mounted on a hollow shaft which is free to turn on said engine-shaft, a speed-changing mechanism mounted on said frame and connecting said clutch to a bevel pinion, an operating lever for said speed-changing mechanism, two bevel gears mounted loosely on a counter-shaft on opposite sides of the bevel pinion, a sliding clutch sleeve splined on said counter-shaft between the two bevel gears, a main operating lever, and connections from the latter to the engine-clutch and to the sliding clutch on the counter-shaft, whereby the engine clutch will become engaged when the sliding clutch on the counter-shaft is thrown into engagement with either of the two bevel gears, said connection being so constructed that the clutch adjacent the engine is closed subsequent to the engagement of the clutch on the counter-shaft with the beveled gears, a pair of power-transmitting gears for connecting said counter-shaft and sliding clutch to the axle of said roller, and a differential gear in driving relation to said traction wheels, substantially as described.

5. In a power-propelled road-roller, the combination with a frame, a steering wheel

swiveled in the forward end, an axle and pair of traction wheels supporting the rear end thereof, of a motor and motor-shaft mounted on said frame, a clutch and hollow shaft mounted forward of said motor, a speed-changing mechanism mounted forward of said motor and connecting said clutch and hollow shaft with a bevel pinion, an operating lever for said speed-changing mechanism, two bevel gears mounted loosely on a counter-shaft on opposite sides of the bevel pinion, a sliding clutch splined on said counter shaft, a spring-balanced lever for said last clutch, a hand-lever, and connections between said hand-lever and clutches to simultaneously operate the latter, said connections being so constructed that the clutch adjacent the motor is closed subsequent to the engagement of the clutch on the counter-shaft with the beveled gears, substantially as described.

6. In a power propelled road roller, the combination with a frame, a steering wheel in the forward end thereof, an axle and pair of traction wheels mounted thereon supporting the rear end of the frame, of a motor and motor shaft mounted on said frame, a transmission shaft, a friction clutch between the motor shaft and the transmission shaft, a reversing gear between the transmission shaft and the axle, a lever, connections between said lever and said reversing gear and connections between said lever and said friction clutch, said last named connections including a link disposed

so as to close the friction clutch when the lever is moved in either direction for causing a forward or rearward drive.

7. In a power propelled road roller, the combination with a frame, a steering wheel 40 in the forward end thereof, an axle and pair of traction wheels mounted thereon supporting the rear end of the frame, of a motor and motor shaft mounted on said frame, a transmission shaft, speed changing mechanism 45 between the transmission shaft and the motor shaft, a friction clutch between the speed changing mechanism and the engine shaft, a reversing gear between the transmission shaft and the axle, a lever, connections 50 between the lever and the reversing gear whereby said gear may be shifted for a forward or rearward drive, connections between said lever and said friction clutch including a longitudinal reciprocating rod, 55 a link pivotally connecting said rod to said lever, said link being so disposed as to move to the opposite sides of the longitudinal axis of the rod upon the shifting of the lever to throw the reversing gear whereby said friction clutch may be closed upon the movement of the reversing gear in either direction and subsequently to the engagement of the reversing gear with its co-acting gear.

In testimony whereof I affix my signature 60 in presence of two witnesses.

LAWRENCE B. WEBSTER.
